UNITED STATES PATENT OFFICE

2,316,683

APPARATUS FOR LOADING SHEATHED
WIRE HEATING UNITS

Frank E. Finlayson, Ontario, and Edwin C. Chapman, Upland, Calif., assignors to General Electric Company, a corporation of New York

Application September 23, 1940, Serial No. 358,018

10 Claims. (Cl. 226—23)

This invention relates to electric heating units of the sheathed type and has for its object the provision of improved apparatus for loading heating units of this character with a suitable insulating material.

This invention has particular application to electric heating units wherein a helical resistance conductor is encased by the sheath and is embedded in and held in spaced relation with the sheath by means of an electrically insulating, heat conducting, refractory material such as powdered magnesium oxide. One heating unit of this character is described in United States Patent No. 1,367,341, issued February 1, 1921, on an application filed by Charles C. Abbott.

It is an object of this invention to provide an improved loading machine of this character in which a plurality of separate loading mechanisms are mounted on a single rotatable table which is rotated so that the separate loading mechanisms come successively before the operator for removing the loaded units and mounting the unfilled units whereby the operator can sit comfortably in one position before the machine and by having the necessary parts, such as the sheaths and coil assemblies, placed conveniently at hand can work at a high efficiency.

It is a further object of this invention to provide an improved loading apparatus having a plurality of separate loading mechanisms all of which are fed from a single storage bin or hopper for the insulating material.

It is a further object of this invention to provide new and improved loading mechanisms for use in such multiple loading apparatus, said loading mechanisms being constructed and arranged so that everything is cleared from the front of the mechanism which can interfere with the mounting of a unit to be loaded thereon whereby the sheath and heater coil may be simply and quickly mounted in their loading position on the individual loading mechanisms.

It is a further object of this invention to provide new and simplified means for starting and stopping the loading operation in accordance with the position of the centralizing member of the loading mechanism.

It is a further object of this invention to provide new and improved means whereby units which have become stuck during the loading operation may be quickly and readily removed from the machine to correct the difficulty.

It is a further object of this invention to provide a single cam mechanism for causing the oscillation of each of the separate loading mech-

anisms and to provide means whereby the connection between the cam mechanism and the loading mechanism may be manually broken so as to stop the oscillation of any one of the separate loading mechanisms without interfering with the operation of the remainder.

It is a further object of this invention to provide new and improved means by which a single driving motor may be employed for driving the cam mechanism at one speed and the supporting table at a greatly reduced speed.

It is a further object of this invention to provide a new and improved multiple unit loading apparatus which is relatively simple in construction and easily and efficiently operated by which sheath type heating units may be properly loaded with insulating material at a more rapid rate.

Additional objects and advantages of this invention will become apparent as the following description proceeds and the features of novelty which characterize this invention will be set forth in the claims appended to and forming a part of this specification.

In accordance with this invention, there is provided a new and improved multiple loading apparatus having a rotatably mounted supporting table. Provided on this table is a plurality of separate loading mechanisms which are adapted to be rotated with the table so that the mechanisms pass in succession before a station at which the operator stands. The supporting table is adapted to be driven by suitable means and the speed of rotation is adjusted so that a single unit mounted in one of the loading mechanisms will be completely loaded in approximately the time required by the table to make approximately three-quarters of a revolution. Centrally arranged with respect to the loading mechanisms is a hopper or storage bin from which the powdered insulating material is supplied to each of the separate loading mechanisms. The individual loading mechanisms comprise means for holding the sheath of a sheath type heating unit in a substantially upright position and means for holding the heating element which is located within the sheath in proper relation to the sheath. Both of these means are adapted to be releasably secured to the loading mechanism so that in the event of the sticking of a portion of the loading mechanism in the sheath during a loading operation the entire assembly may be removed from the mechanism and cleared. With the sheath and heating unit mounted in their proper position, means are provided for feeding to the sheath the powdered magnesium oxide at

a regulated rate. A centering device, called a centralizer, is arranged to be inserted within the sheath to hold the portions of the resistance element in the center line of the sheath while it is being loaded. This centralizer is driven with a reciprocatory motion up and down in the sheath as the insulating material is being fed thereto by oscillating means. In accordance with this invention new and improved means are provided for driving both the supporting table for the loading mechanisms and the oscillating means for the loading mechanisms from a single driving motor. Improved means are provided for controlling the flow of insulating material to the sheath in accordance with the position of the centralizer in the sheath. Also simplified means are provided for stopping the reciprocatory movement of the oscillating means at any time during the loading operation.

For a more complete understanding of this invention, reference should be had to the accompanying drawings in which Fig. 1 is a fragmentary front elevation, partly in section, of a multiple loading apparatus arranged in accordance with this invention; Fig. 2 is a fragmentary side elevation of the apparatus shown in Fig. 1; Fig. 3 is a fragmentary top view of the apparatus shown in Fig. 1 with the base and motor drive removed; Fig. 4 is an enlarged fragmentary front elevation showing details of the upper portion of one of the individual loading mechanisms mounted on the multiple loading apparatus shown in Figs. 1-3; Fig. 5 is a view similar to Fig. 4 with parts removed to show details of the upper portion of the oscillating mechanism for single loading mechanism; Figs. 6, 7, 8 and 9 are sectional views taken through the lines 6-6, 7-7, 8-8 and 9-9, respectively, of Figs. 4 and 5 and looking in the direction of the arrows associated with these lines; Fig. 10 is an enlarged fragmentary front elevation showing details of the middle portion of one of the individual loading mechanisms mounted on the multiple loading apparatus shown in Figs. 1-3; Figs. 11, 12 and 13 are sectional views taken on the lines 11-11, 12-12 and 13-13, respectively, of Fig. 10 and looking in the direction of the arrows associated with these lines; Fig. 14 is an enlarged fragmentary front elevation showing details of the bottom portion of one of the individual loading mechanisms mounted on the multiple loading apparatus shown in Figs. 1-3; Fig. 15 is a side elevation of the portion of the apparatus shown in Fig. 14; Fig. 16 is a sectional view taken on the line 16-16 of Fig. 15 and looking in the direction of the arrows; Fig. 17 is a detail view showing details of the latch mechanism for latching the oscillating mechanism out of contact with its operating means; Fig. 18 is an enlarged fragmentary sectional view of the base of the apparatus shown in Figs. 1-3 showing details of the driving and oscillating mechanism arranged in accordance with this invention; and Fig. 19 is a fragmentary elevation, partly in section, of a finished heating unit of the type to which this invention is particularly applicable.

Referring to the drawings, this invention has been illustrated in one form as applied to apparatus for loading electric heating units of the sheathed type, such as described in the above-mentioned Abbott patent. A heating unit of this type has been illustrated in Fig. 19; this unit comprises a helical resistance element 10 encased by a metallic sheath 11. Suitable terminals 12 are mechanically and electrically connected to the

ends of the resistance conductor 10. For this purpose, the resistance conductor is threaded on the terminals, as shown, and as fully described in United States Patent No. 1,494,938 to C. C. Abbott, dated May 30, 1924. The resistance conductor 10 is embedded in and is held in spaced relation with reference to the sheath 11 by a highly compacted mass 13 of heat conducting, electrically insulating, refractory material, such as powdered magnesium oxide. The powdered magnesium oxide is compressed into a dense compact mass in any suitable way as by reducing and elongating the sheath. The mass of insulating material 13 functions to hold the resistance element 10 in spaced relation with reference to the sheath, preferably so that its axis coincides with the axis of the sheath. It also functions to conduct heat from the resistance element 10 to the sheath. The inner ends of the terminals 12 are embedded in the powdered insulating material 13, as shown, so that they are insulated from the sheath 11 and are held in spaced relation with it by means of the insulating material.

This invention relates to a new and improved multiple loading apparatus for loading heating units of the aforementioned type with the powdered magnesium oxide material. This apparatus comprises a base plate 14 mounted upon suitable legs 15. Mounted on the base plate is a driving motor 16, the function of which will be described more fully hereinafter, and a cylindrical pedestal 17. Rotatably mounted on the upper surface of the pedestal 17 is a substantially circular frame or table 18. Suitable ball bearings 19 are provided for allowing practically frictionless rotation of the frame 18 relative to the pedestal.

The rotatable frame or table is adapted to support the remainder of the superstructure of the loading apparatus shown in Figs. 1 and 2. This superstructure includes a plurality of separate loading heads or mechanisms which are adapted to rotate with the table 18. Details of the individual loading mechanisms will be described more fully hereinafter. In the specific form of my invention illustrated, five such individual loading mechanisms are mounted on the table 18 but it is to be understood that this invention is not limited to any specific number of such separate mechanisms.

Supported at the upper end of the superstructure by means of bracket 20 and centrally arranged with respect to the separate loading mechanism is a bin or hopper 21 in which is stored the powdered magnesium oxide. Extending outwardly from the bottom of this hopper is a plurality of conduits 22 for feeding the magnesium oxide to the separate loading mechanisms and provided at the top of the hopper is a removable cover 23. In order to insure the free flow of the magnesium oxide through the feeding conduits 22 there is mounted on the lower end of the hopper an electric heating coil 24. This heating coil 24 is sufficiently large to heat the magnesium oxide and drive off any moisture which might tend to form lumps in the insulating material near the outlet of the hopper. Provided at the extreme lower end of the hopper is a drain tube 25 which is closed by a cap 26. By removing the cap 26 it is possible to empty the hopper completely if the machine is to be shut down for any length of time. Also the tube 25 permits access to the bottom of the hopper for the purpose of removing or breaking up any obstruction formed near the lower end thereof.

Referring to Fig. 3, it will be observed that the individual loading mechanisms are symmetrically spaced about the hopper and since these mechanisms as well as the hopper are all supported by the table 18, they will rotate as the table is rotated.

In general, the individual loading mechanisms mounted on the rotating table 18 are similar to the type of loading mechanism described and claimed in the copending application of John L. Andrews, Serial No. 347,446, filed July 25, 1940, which is assigned to the same assignee as this invention, and which discloses and broadly claims certain features disclosed in this application. However, in accordance with this invention, improvements have been made in the type of loading mechanism there described and claimed with a view to obtaining a simpler and more easily operated loading mechanism which is specially suited for use in the new and improved multiple loading mechanism of this invention.

Referring now to Figs. 4-15, it will be observed that the improved individual loading heads or mechanisms of this invention comprise two vertically extending lower supporting plates 26 and 27 (Fig. 14) which are secured to the turn-table 18 by means of bolts 28. Secured to the upper end of these plates by means of suitable machine screws 29 is an upper vertically extending supporting plate 30. Mounted on the upper end of the plate 30 is a member 31 (Figs. 4 and 7). Provided on each of the edges of the upper supporting plate is an outwardly extending guide or flange 32 and provided in each of these flanges is a groove 33. As will be more fully described hereinafter, these grooved flanges serve as guides for a movable carriage. As shown in Fig. 2 the guides 32 extend along the edges of the plate 30 for over half the length of the plate. Spaced below the bottom of the left-hand guide and extending down the remaining portion of the left-hand edge of the plate 30 is a third guide flange 34 which extends downward below the lower edge of this plate, as shown in Fig. 14, and is secured near its lower end to the supporting plate 26 by means of the bracket 35 and bolt 36. As shown in Fig. 14, the guide flange 34 is provided with a groove 37 on each of its lateral faces for a purpose which will be described hereinafter.

Mounted within the confines of the guides 32 is the carriage 38 which comprises a substantially U-shaped metallic member having mounted thereon a plurality of rollers 39 having flanges 40 which are adapted to engage the grooves 33 provided in the guide members, as shown in Fig. 8, so as to confine the motion of the carriage 38 to a substantially vertical path.

Mounted on the lower supporting plates 26 and 27 is a substantially L-shaped bracket 41 which is secured to the plates by suitable means such as the bolts 42. Mounted on this bracket is a supporting standard for the lower end of the sheath 11 which is to be loaded with insulating material. The supporting standard comprises a sleeve member 43 which extends downwardly through a suitable opening provided in the bracket 41 and an adjustable central member 44 which extends through the sleeve member and may be adjusted to different positions to accommodate sheaths of different lengths. The sleeve 43 is secured to the bracket 41 by means of the nut 45. Provided on the upper end of the central member 44 is a substantially mushroom-shaped head member 46 having a depending skirt 47 which telescopically engages an upwardly pro-

jecting collar 48 provided on the upper end of the sleeve 43. Located in the recess formed by these telescopically engaging portions of the head and sleeve is a compression spring 49 which serves to bias the head member in an upward direction. Provided on the upper portion of the head member 46 is an upward cylindrical extension 50 which is arranged to be inserted in the lower end of the sheath as is clearly shown in Fig. 14.

The terminal 12 at the lower end of the sheath is supported in its central position with reference to the sheath by means of a suitable head 51 which is rigidly secured to the terminal and is received in a recess 52 bored in the lower end of the sheath. The cylindrical extension 50 is adapted to be received in the recess 52 whereby the lower end of the sheath is centered and held against lateral displacement.

It is, of course, understood that before the heater sheath 11, resistance conductor 18 and terminals 12 are inserted in the loading apparatus the resistance conductor will have been secured to the lower and upper terminals 12 and they will have been threaded through the sheath so as to bring the head 51 on the lower terminal into the recess 52 provided in the sheath.

The upper terminal is secured by suitable releasable means (not shown) to a terminal supporting rod 53 which extends vertically upward to the top of the loading mechanism as shown in Fig. 4. Secured to the top end of the rod 53 by means of set screw 54 is a block 55 having upper and lower head portions and a central portion which is adapted to be received in a recess 56 provided in the upper plate 31. This block is removably held in the recess 56 by means of a latch arm 57 which is rotatably mounted on the upper plate by means of a screw 58. It will be understood that when the latch arm is in the position shown in Fig. 4 the block will be latched in the recess in the top plate and the upper end of the terminal rod will be securely held in position. However, when the latch arm is rotated through 90 degrees, the block 55 may be readily removed from the recess to free the upper end of the terminal rod.

Arranged to operate around the resistance conductor within the sheath is a centralizing member 59. Referring to Fig. 11, it will be observed that the centralizing member is substantially cylindrical in form and is provided with a series of vertically arranged and circumferentially spaced ribs 60 on its outer surface. These ribs are adapted to engage the inner wall of the sheath 11 when the centralizer is inserted therein. It will be understood that a running clearance will be provided between these ribs and the sheath and it will be further understood that the centralizer is provided with a central aperture (not shown) which fits about the helical coil 10. In this way the centralizer rises during the loading of the sheath and maintains the central axis of the coil substantially coincident with the central axis of the sheath.

The centralizer 59 is threaded upon the lower end of a centralizing tube 61 which surrounds the terminal supporting rod 53 and extends upwardly to a point near the top of the loading mechanism. In order to support the upper end of the centralizer tube, a plate 62 having a recess 63 is provided on the central portion of the front surface of the carriage 38 as shown in Figs. 4 and 8. Arranged to be received in the recess 63 is a block 64 through which the

upper end of the centralizer tube is adapted to extend. This block is provided at its lower end with a split nut construction 65 for rigidly clamping the block to the centralizer tube. In order to support the block removably in the recess 63, there is provided a manually operated latch arm 66 which is similar to the latch arm 67 for the terminal rod and is secured to the plate 62 by means of the screw 67. When the arm 66 is in the position shown in Fig. 4, the block will be latched in the recess and when the arm is rotated through 90 degrees the block may be readily removed from the recess so as to free the upper end of the centralizer tube.

The upper end of the sheath 11 is rigidly secured in the apparatus in its proper position with relation to the resistance conductor 10 by means of a pair of jaws 68 which are pivotally mounted at 69 on a plate 70 which is secured to the front wall of the supporting plate 30 as shown in Figs. 10, 11 and 13. These jaws are provided with a pair of hardened metal inserts 71 which together with the insert 72 mounted in the plate 70 function as abutments for the upper end of the sheath when the jaws are closed, as clearly shown in Figs. 10 and 11. Below the inserts 71 the jaws will be provided with arcuate portions 73 which are adapted to fit tightly about the upper end of the sheath. Gear members 74 having intermeshing teeth 75 are secured to the lower ends of the jaws to insure simultaneous operation thereof.

In order to move the jaws with a positive snap movement between the fully open and fully closed position, there is provided a snap action mechanism which is similar to that described in the above-mentioned copending Andrews application. This snap action mechanism comprises a pair of over center springs 76 (Fig. 13) which are of the compression type and have their opposite ends bearing on collars 77 and 78 respectively. The collars are provided with knife-edge slots 79 which receive knife-edge bearings 80 provided on the arms 81 attached to the jaw members. The opposite collars 78 are mounted on pivot bearings 82 which are adjustably mounted upon a supporting bracket 83 which in turn extends through an opening 84 provided in the plate 30 and is rigidly secured to an intermediate T-shaped plate member 85 which is secured to the plate 70. As shown in Fig. 13, the bracket 83 is substantially T-shaped and between its inner end and the plate member 85 there is provided a plate 86 which functions as a stop for the jaw arms 81 when the jaws are in their fully open position. It is, of course, understood that the projecting portions of the jaw arms extend through the opening 84 provided in the plate 30 so that they may engage the compression springs which are located on the back of the plate.

Referring now to Figs. 1 and 11, it will be observed that the supply tube 22 leading from the hopper 21 discharges into an opening in a member 87 which is secured to the rear wall of the plate 30. The opening in member 87 in turn discharges into a passageway 88 formed in the plates 30, 85 and 70. This passageway discharges into the jaws 68 directly above the open end of the sheath 11. A suitable tongue-like cut-off gate 89 is placed over the mouth of the passageway 88 to control the flow of insulating material to the sheath.

Arranged for operating the cut-off gate 89 between its open and closed position, is a cut-off 75

actuating lever 90 (Figs. 2, 10 and 11) which is pivotally mounted upon the plates 89 and 30 by means of the screw fastening device 91. The cut-off gate 89 is secured to the actuating lever 5 by means of a block 92 (Fig. 11) which is rigidly secured to the upper portion of the gate and which carries a pin 93 which is received in a slot provided for it in the actuating lever. The 10 actuating lever is biased to move in a counterclockwise direction as viewed in Figs. 2 and 10, that is, in a direction to open the gate, by means of a spring 94 which is secured at its lower end to the lever as shown in Fig. 10. The other end of the biasing spring is anchored to a pin 95 which is fixed to the supporting plate. An adjustable stop 96 is secured to the left-hand side of the plate 70 (see Fig. 10) to limit the counterclockwise movement of the lever 90 under the influence of spring 94.

The cut-off actuating lever 90 is prevented from moving in its counterclockwise direction by means of a latch 97 which engages an abutment 98 formed in the lever. The latch 97 is pivotally mounted on a pivotally mounted actuating arm 99 by means of a stud 100. The latch 97 may be rotated in a counterclockwise direction with respect to the arm 99 but is prevented from turning in a clockwise direction with respect to the arm from the position shown in Fig. 10. A weight 101 normally biases the latch to its position shown in Fig. 10. The arm 99 is keyed to a pin 102 which extends through the support 30 and has its opposite end rotatably supported in a substantially Z-shaped bracket 103 which is secured to the rear side of the support by means of a bolt 104 (Fig. 12). A suitable spacer 105 is provided to space the arm 99 away from the front surface of the support 30.

The arm 99 is moved to its unlatching position 40 to permit the lever 90 to open the feed gate 89, that is, is moved in the counterclockwise direction as viewed in Fig. 10, by means of a control arm 106 which is keyed to the pivot pin 102 and lies on the back side of the main supporting surface 30 between this surface and the surface of the Z-shaped bracket 103 in which the outer end of the pin 102 is journaled (see Fig. 12). The arm 106 includes an outwardly projecting portion which projects beyond the left-hand edge of the supporting plate as viewed in Figs. 10 and 12. In order to cause the movement of the arm 99 to take place quickly and with a snap action in accordance with a small movement of the control arm 106 there is provided a compression spring 107 which is similar to the compression springs used for operating the jaws 68 with a snap action. This compression spring is confined between the collars 108 and 109. The collar 108 is provided with a knife-edge slot which receives the knife-edge bearing 110 provided on the control arm 106. The opposite collar 109 engages a pivot bearing 111 which is adjustably mounted on a flange 112 secured to the rear side of the supporting plate 30 as shown in Fig. 12. In order to limit the movement of the arm 106 under the influence of the snapping spring 107, a pair of stops 113 and 114 are threadedly mounted in a pair of flanges 115 and 116 respectively which are mounted on the rear portion of the plate 30 so as to lie on opposite sides of the control arm (see Fig. 11).

When the projecting portion of the control arm 106 is moved downwardly from the position shown in Fig. 10, the arm 99 will be rotated a limited amount in the counterclockwise direction

as viewed in Fig. 10 and this rotation will take place quickly and with a snap action under the influence of the compression spring 107. The extent of the counterclockwise rotation will be sufficient to move the latch 97 off the projection 98 of the cut-off actuating lever 90 to permit this lever to be moved in a counterclockwise direction by the spring 94 whereby the gate 89 will be moved to its open position. The extent of the counterclockwise movement of the arm 99 will be limited by the distance between the fixed stops 113 and 114. When the operating handle is moved upwardly from the lower position just described, the arm 99 will be rotated in a clockwise direction so that the latch 97 will engage the abutment 98 to hold the lever 90 in the position in which the gate 89 is closed.

Mounted on the carriage 38 is an outwardly projecting L-shaped plate 117 to which is secured a downwardly extending rod 118. As shown in Fig. 10, this rod terminates at substantially the level of the gate operating lever 90 and supported at the lower end of this rod is a second carriage comprising the transverse plates 119 and 120 and the vertical plate 121. The plate 121 lies on the opposite side of the guide 34 from the rod 118 as shown in Fig. 10. Provided on the lowermost portion of this carriage is a pair of rollers 122 which are adapted to lie on opposite sides of the guide 34 and to track in the slots 37 provided in this guide. Provided on the rod 118 intermediate the second carriage and the upper end of the rod is a pair of adjustable stops 123 and 124 which are adapted to engage the projecting portion of the control arm 106 so as to cause the arm automatically to be rotated in accordance with a predetermined downward or upward movement of the carriage 38. These stops are provided with set screws 125 so that they may be adjusted to their proper position on the rod.

Provided on the inner edge of the vertical plate 121 is a cam surface 126 which is adapted to be engaged by a cam roller 127 mounted on the left-hand corner of the cut-off actuating lever 90 as shown in Fig. 10. The cam surface 126 is arranged so that when the carriage 38 is in its upper position, as shown in Fig. 4, the roller 127 will ride on the highest part of the cam surface so that the lever 90 is rotated in the clockwise direction. This movement of the lever 90 will, of course, cause the gate 89 to be moved to its closed position and will also permit the latch 97 to move into engagement with the abutment 98 to hold the lever in its latched position.

With the arrangement described thus far, it will be seen that during a loading operation the sheath 11 and the resistance coil 10 are held in their properly aligned relation whereas the centralizer 59 and the centralizer tube 61 which are connected to the movable carriage 38 may be moved downwardly within the sheath. This downward movement of the carriage 38 also causes the rod 118 and the carriage connected thereto to be moved downwardly. In this latter downward movement the roller 127 moves completely off the cam surface 126 so that if and when the latch 97 is removed, the cut-off actuating lever 90 may be rotated counterclockwise under the influence of the spring 94 to cause the gate 89 to be open and initiate the flow of insulating material into the sheath. The upper stop 124 provided on the rod 118 is positioned so that, when the centralizer 59 is adjacent the bottom of the sheath unit being loaded, it will engage the projecting portion of the control arm 106 to

cause it to be moved downward whereupon the arm 99 is rotated counterclockwise as viewed in Fig. 10 with a snap action as described above. This, of course, permits the actuating lever 90 to be rotated counterclockwise to open the gate. As the sheath is loaded with insulating material, the centralizer 59 and the carriage 38 are moved upwardly as will be described below. After a predetermined upward movement, the roller 127 will reengage the cam surface 126 to decrease progressively the flow of insulating material into the sheath in accordance with the shape of the cam surface 126 shown in Fig. 10. When the sheath is completely loaded, the carriage will be moved upwardly an amount sufficient to cause the roller to engage the highest surface of the cam so that the gate is completely closed. The lower stop 123 provided on the rod is positioned so that when the gate has been closed by the cam surface the projecting portion of the control arm 106 will engage this stop and be moved upwardly so as to cause the arm 99 to be moved in a clockwise direction to move the latch 97 to its latching position shown in Fig. 10.

Secured to the top transverse plate 119 of the carriage mounted on the rod 118 is an outwardly projecting operating handle 128 by means of which the upper carriage and the centralizer tube connected thereto may be lowered. Pivotedly mounted on this operating handle and lying below the handle is a latch release handle 129 which operates to release a latch 130 which is adapted to engage the top edge 131 (see Fig. 11) of the guide member 34 to hold the carriage in its upper position. By moving the release handle upward relative to the operating handle, the latch 130 will be moved off the upper edge 131 of the member 34 so that the carriage is free to move downwardly. This constitutes the first operation in the use of the loading mechanism.

During the filling of the sheath 11 the carriage 38 and the centralizer tube 61 connected thereto are adapted to be moved with a reciprocatory motion up and down with reference to the frame, the carriage 38 tracking in the guides 32. This reciprocatory movement is transmitted through an oscillating mechanism which is adapted to oscillate in a path parallel to the front surface of the member 30. This mechanism comprises a pair of vertically extending parallel plates 132 and 133 which are separated by the control member 134. As shown in Figs. 5 and 6, the upper end of the member 134 terminates a substantial distance below the upper end of the plates 132 and 133 so that a channel portion is defined by the upper plates. Arranged to space the extreme upper end of these plates is a cross bar 135 which is suitably secured to the plates as by means of rivets 136. In order to guide the reciprocatory movement of the upper end of the oscillating mechanism, a slot 137 is provided in the upper end of the supporting plate 30. Welded to the cross bar 135 is a pin 138 which is provided with a circular member 139 of increased diameter which is adapted to track in the slot 137. In order to maintain the circular member 139 in its proper relation with respect to the slot there is provided on the outer end of the pin 138 a washer 140 which overlaps the adjacent portion of the back surface of the supporting member 30. This washer is mounted in position on the pin by means of the nut 141.

Provided in both of the plates 132 and 133 near the upper end thereof are elongated slots 142 (Figs. 5 and 6) and projecting into these

slots are bearing members 143 which have flat surfaces engaging the flattened side wall of the slot. These bearing surfaces are integrally formed on the upper end of a bifurcated member 144 which lies between the plates 132 and 133 as shown in Figs. 5, 6 and 9. The bearing members are provided with a centrally located aperture and extending through this aperture is a shaft 145 upon which is mounted a sprocket 146. Extending around the sprocket is a link 147 which is preferably in the form of the ordinary bicycle chain.

In order to adjust the tension of the chain 147 the bearings for the sprocket are vertically adjustable in the slots 142 provided in the plates. To obtain this adjustment a block 148 is riveted between the plates 132 and 133 and threadedly mounted in this block is an adjusting screw 149 which is provided at its outer end with a dowel that projects into a socket in the lower end of the bifurcated bearing support 144. The adjusting screw 149 is held in its adjusted position by means of a lock nut 150. A suitable opening 151 is provided in the plate 132 so that access may be had to the adjusting screw and lock nut to permit adjustment of the tension in the chain.

In order to transmit the motion of the oscillating mechanism to the carriage, an offset bracket 152 is secured to the rear face of the carriage 38 by suitable means such as rivets 153. This bracket is provided with a recessed opening 154 which conforms in size and shape to a single link of the chain 147 and as shown in Fig. 5 the link 155 of the chain is mounted in this recess.

The construction of the lower portion of the oscillating mechanism is more clearly shown in Figs. 10 and 11. Referring particularly to Fig. 11, it will be observed that the front and back plates 132 and 133 respectively are secured to the central member 134 near this end by means of rivets 156 and that the rear plate extends downwardly a substantial distance below the front plate. The central member also extends downwardly the same distance as the rear plate and it is provided intermediate the end of the front plate and the rear plate with a recessed portion 157 (Fig. 11). In order to guide the reciprocatory movement of the lower end of the oscillating mechanism there is secured to the rear face of the back plate 133 a U-shaped trapezoidal member 158 on which is rotatably mounted a pair of rollers 159. Mounted on the back wall of the supporting plate 30 is a pair of guide members 160 and 161 which are provided with grooves 162 in which the rollers 159 are adapted to track. It is to be observed that a suitable opening is provided in the supporting plate for receiving the guide roller supporting member 158. This opening is made sufficiently long to permit free reciprocatory movement of the member 158.

Provided on the front wall of the lower end of the central member 134 is an L-shaped plate 163. This L-shaped plate and the roller supporting plate 158 are secured to the plates 132 and 133 by means of the pair of machine screws 154.

In the opening defined by the recessed portion 157 of the central plate and the L-shaped plate 163 there is mounted a lower sprocket 165 and a ratchet wheel 166, which are secured together by means of pins 167 as shown in Fig. 11 and which are mounted to rotate on a shaft 168 rotatably supported in the plates 163 and 133 and 134. A pawl 169 (Fig. 10) is arranged to cooperate with the ratchet wheel 166. This pawl

is rotatably mounted on a pawl arm 170 which is pivotally mounted on a bearing member 171 that is mounted between the upper end of the L-shaped plate 163 and the central plate 134 as clearly shown in Fig. 11. A spring pressed plunger 172 normally holds the pawl from rotat-

ing. With the parts of the oscillating mechanism described thus far, it is to be observed that if the pawl 169 is out of engagement with its ratchet wheel 166, the sprockets 165 and 146 will be free to rotate. Under these conditions, the oscillating mechanism will be reciprocated independently of the carriage 38. If, however, the pawl is moved into engagement with its ratchet wheel, the sprocket 165 will be locked against rotation and hence the carriage 38 and the centralizer tube mounted thereon will be reciprocated with the oscillating mechanism. The pawl 169 is biased by the weight of the pawl lever 170 to move into engagement with the ratchet wheel but is restrained from doing so by means of a cylindrical member 173 mounted on the upper end of the arm 99. This cylindrical member is positioned to engage an extension 174 provided on the pawl lever as shown in Fig. 10. Thus engagement of the pawl 169 with the ratchet 166 is prevented until the arm 99 is moved in a counterclockwise direction as viewed in Fig. 10 to release the cut-off actuating lever 90 as described above. This movement of the arm 99, as previously described, is controlled by control arm 106 and the pawl 169 will be free to move into engagement with the ratchet 166 so long as the arm 99 is in its non-latching position relative to lever 90 for controlling of the feed of the insulating material.

In order to impart a reciprocatory movement to the oscillating mechanism described in detail above, there is provided in the lower end of this mechanism a stud shaft 175 which projects outwardly beyond the rear surface of the supporting plate 30. Connected to this shaft is a connecting or push rod 176 which extends downwardly in the direction of the rotatable table 18. Provided in the top plate 177 of the table is an opening through which is inserted a sleeve 178 which is secured to the top plate 177 by means of bolts 179 which pass through flanges 180 formed on the sleeve (see Fig. 18). Provided in the sleeve is a central opening through which passes a follower rod 181. The lower end of the push rod 176 is adapted to be secured in threaded engagement with the follower rod 181 and it will be understood that sufficient clearance is provided between the follower rod and the sleeve to permit the reciprocatory movement of this rod. In order to prevent the insulating powder from interfering with the movement of the follower rod in the sleeve there is provided a corrugated cap 182 which extends over the upper end of the sleeve 178 and engages the rod 176. This cap is made from some suitable resilient material such as rubber. Provided on the lower end of the follower rod 181 is a rotatably mounted follower member 183 which is adapted to engage the surface 184 of an edgewise cam 185 mounted below the surface 177 of the table 18. It is to be understood that while the details of only one connecting and follower rod assembly are shown in Fig. 18, there will be one such assembly for each of the plurality of separate loading mechanisms supported on the rotatable table.

It is obvious that if the edgewise cam 185 is rotated, the follower rod is reciprocated an

amount equal to the difference in height between the lowest and highest surface of the cam. This reciprocatory movement of the follower rod is transmitted through the connecting rod 176 to the stud shaft 175 and thence to the oscillating mechanism previously described.

Means are provided for manually moving the follower rod upwardly an amount sufficient to prevent engagement of the follower 183 with the cam surface 184 to stop the reciprocatory movement of the oscillating mechanism. This means comprises a bell crank lever 186 (Figs. 14 and 15) which is pivotally mounted on the lower supporting plate 27. This lever is provided with a short arm 187 which is adapted to extend under a stop 188 which is secured to the lower end of the connecting rod 176 by means of a set screw 189. The long arm of the bell crank is provided with an outwardly extending handle 190 and mounted on this handle is a latch member 191 which is adapted to engage the edge of the supporting plate 27. This latch is biased to its latching position by means of the resilient member 192.

Normally the bell crank lever is in the position shown in full lines in Fig. 15 and when in this position the follower 183 engages the surface 184 of the cam. When the bell crank lever is pulled forward or to the left, as viewed in Fig. 15, to the dotted position shown in this latter figure, an upward force is exerted on the stop 188 and the connecting rod 176 is raised an amount sufficient to move the follower off the edgewise cam. This will, of course, also cause the oscillating mechanism and the carriage mounted thereon to be raised. When the lever is in the position dotted in Fig. 15, the latch member will engage the edge of the support 27 as shown in Fig. 17, and the connecting rod will be held in its raised position.

As shown in Figs. 11 and 14, a spring 193 is provided for biasing the connecting rod 176 downwardly so that the follower 183 will accurately follow the surface of the edgewise cam 185. This spring is connected at one end to a strap 194 (Fig. 11) secured to the connecting rod by means of the bolt and nut 195. The opposite end of the spring is secured to a bolt and nut 196 provided on a vertically extending bracket 197 which is mounted on the table 177 by means of a bolt 198 as shown in detail in Figs. 14 and 15.

The motor 16 is adapted to drive both the turntable and the edgewise cam through a suitable speed reducer 199. Considering this construction in more detail and referring to Figs. 1, 2 and 18, it will be observed that there is provided on the base 14 a bracket 200 in which is journaled a shaft 201 which is connected to the speed reducer 199. This shaft is provided with a sprocket 202 which is driven by means of a suitable chain 203 from a second sprocket 204 mounted on the end of the motor shaft.

In accordance with this invention, I have provided improved means for using the single driving mechanism described above for imparting a relatively high speed to the edgewise cam and a relatively low speed to the table and superstructure. Referring now to Fig. 18, it will be observed that this is accomplished by means of a differential gear arrangement which comprises four small gears 205, 206, 207 and 208 and two large gears 209 and 210. Considering this construction in more detail, it will be observed that the cam plate 185 is provided with three vertical sleeves which include a central sleeve 211 and two outer sleeves 212. The central sleeve is adapted

to receive a shaft 213 which extends vertically upward from the speed reducer. Extending through this sleeve and through the shaft mounted therein is a tapered pin 214 which is provided for holding the two in fixed relation. Mounted in the outer sleeves 212 are ball bearing members 215 in which are journaled the shafts 216. Mounted on the lower end of these shafts are the gears 207 and 208 and mounted on the upper end are the gears 205 and 206. The central hub 211 is adapted to extend upwardly above the top of the drive shaft 213 and journaled in this upwardly extending portion of the hub is the large gear 210 which is rigidly secured to the top plate 177 of the table 18 by means of the bolts 217. The lower gears 207 and 208 are adapted to mesh with the teeth provided on the large gear 209 which is fixed to a plate 218 by means of the machine screws 219. The plate 218 is adapted to be secured in any suitable manner to the upper surface of the speed reducer so that it and the gear secured thereto are fixed. In order to rotatably journal the shaft 213 in the plate 218 and the lower fixed gear 209 a suitable sleeve bearing 220 is provided.

In the preferred form of this invention, the differential gear arrangement described above is designed so that the edgewise cam is driven at a rate of about 90 revolutions per minute whereas the table and the entire superstructure secured thereto is rotated at the rate of about one revolution per minute. To obtain this speed differential the upper gears 205 and 206 are provided with 20 teeth, the lower gears 207 and 208 with 40 teeth, the rotatable gear 210 with 45 teeth and the fixed gear 209 with 91 teeth. Thus, the gears 207 and 208 have twice as many teeth as the gears 205 and 206 and the gear 209 has twice as many teeth plus one as the gear 210. Therefore, as the gear 210 is driven and the small gears rotate around the movable gear 210 and the fixed gear 209, the fixed gear drops behind one tooth in each revolution and as the surface upon which the small gears are mounted is rotating at 90 revolutions per minute, which is the speed of shaft 213, the upper gear 210 which is secured to the turntable will make one complete revolution in approximately one minute. Thus the entire superstructure including all of the separate loading mechanisms mounted thereon is rotated slowly. The speed of rotation of the table 18 is regulated relative to the time required for loading a single unit so that the loading will be completed in about three-quarters of a revolution of the table. In this way it is assured that a particular unit will be loaded before the loading mechanism again comes before the operator.

Suitable means are provided for applying to the sheath a plurality of intermittent impacting blows to settle the insulating material as it is fed into the sheath. For this purpose a vibrator 221 (Fig. 2) is provided. The vibrator comprises a straight plunger hammer 222 arranged to tap the sheath as shown in Fig. 2. The plunger hammer is rapidly reciprocated or vibrated and engages the side of the sheath with intermittent impacting blows. The plunger hammer is driven by means of any suitable vibrating mechanism. The vibrating mechanism has not been illustrated in detail for any suitable vibrating mechanism may be used and the details of this mechanism form no part of the present invention. The vibrator 221 is adapted to be firmly secured

to the lower end of the supporting plate 30 as shown in Fig. 2.

In order to strengthen the superstructure at the top, there is provided a substantially circular top plate 223 shown more fully in Fig. 3. This plate is provided with a plurality of peripherally spaced recesses 224 which are adapted to expose a portion of the top of the plate 31 and facilitate the insertion and removal of the terminal rod supporting blocks 55 in the recesses provided in the plate 31.

Suitable slip ring means (not shown) are provided for supplying electrical energy to both the heater unit 24 and the vibrator mechanism 221.

Considering the operation of the improved multiple loading apparatus forming this invention, it will be assumed that the machine is ready for operation and that the motor 16 is running. It will also be assumed that the carriage 38 is in the uppermost position as shown in Fig. 4 and that the latch 130 is in engagement with the surface 131 of the guide rod 34 as shown in Fig. 10. In this position, the lower stop 123 has caused the control arm 106 to be snapped upwardly so that the arm 99 has been moved clockwise and the pawl 169 is out of engagement with the ratchet 168. This allows the oscillating mechanism to oscillate up and down freely under the action of the edgewise cam 185 and the connecting rod 176 without in any way affecting the position of the carriage and the attached centralizer, as previously described.

The operator now slips a sheath 11 up over the centralizer 59 and fastens the top terminal 12 of the coil assembly to the supporting hook (not shown) provided in the centralizer. The operator then draws the sheath down over the coil 10 so that the head 51 of the lower terminal 12 is received in the recess 52 so as to close the lower end of the sheath and also so as to anchor the center of the lower terminal with reference to the sheath. The lower end of the sheath will then be placed upon the head 46 so that the projection 50 on the base is received within the recess 52. The upper end of the tube is then placed in its proper relation in the jaws 68 and these jaws are snapped closed. This completes the assembling of a particular heating coil and sheath in a particular loading mechanism.

The operator next grasps the handles 128 and 129 and moves the handle 129 so that the latch 130 is released. The carriage assembly is then lowered until the centralizer nears the bottom of the tube. At this point, stop 124 which has been previously set, engages the control arm 106 and snaps it down. This causes the lever 98 to be snapped in a counterclockwise direction and this rotation of the lever causes the pawl 169 to engage the ratchet 168 starting the entire assembly attached to the carriage 38 including the centralizer to oscillate up and down. At the same time the lever 98 trips the gate controlling the flow of insulating material and allows the powder to start flowing into the tube. Suitable switch means (not shown) will next be actuated to cause the vibrator to be energized. The switch means may be either manually actuated or actuated in accordance with a predetermined movement of the carriage 38.

As the carriage 38 and the centralizing tube secured thereto are reciprocated up and down, the centralizer 59 will be intermittently carried into engagement with the insulating material, the level of which is continually rising in the sheath. The centralizer will engage the insulat-

ing material on each stroke providing the level has risen high enough to permit the centralizer to contact it. When the centralizer engages the level of the insulating material, its downward movement and hence the downward movement of the centralizing tube and the carriage 38 are resisted. This effects a momentary release of the carriage 38 from the oscillating mechanism for when the downward movement of the carriage is resisted the chain 147 tends to cause a counterclockwise movement of the ratchet 166 which movement is permitted by the relative relation between the ratchet and the pawl 169. On the next stroke the carriage will oscillate about the new level found by the centralizer. This produces a progressively upward movement of the carriage and centralizer as the filling of the tube takes place.

It will be understood that as the centralizing tube rises in the sheath during the filling operation, the ribs 60 on the centralizer will slidably engage the inner walls of the sheath so as to hold the resistance coil 10 centrally within the sheath. Also it will be understood that the insulating material can flow through the centralizer to the portions of the sheath under it through the spaces between the centralizer and the sheath and also down through the resistance coil. It will be further understood that the centralizer exerts some pressure on the insulating material each time it engages it which causes the insulating material both inside and outside of the centralizer to be displaced and moved upwardly. This upward movement of the insulating material tends to elevate the turns of the resistance structure slightly and the force with which the centralizer tube displaces the insulating material is so controlled that it elevates the turns just enough to compensate for the sag of the turns due to their own weight and the weight of the settling insulating material.

Moreover, it will be understood that as the powder level rises during the loading operation and as it is acted on by the oscillating centralizer, the vibrator 221 is continuously functioning to settle the insulating material in the sheath as it is admitted to the sheath. The constant vibratory hammering of the sheath by the vibrator and the controlled rise of the oscillating centralizing tube not only control the uniformity of the spacing of the turns of the winding but also insure a uniform density in the insulating material.

After a predetermined rise of the carriage 38 and the centralizing tube in the manner described above, the roller 127 on the lever 90 will engage the surface 126 of the vertical member 121 so that the gate 89 is progressively closed as the loading of a particular unit nears completion. This produces a gradual reduction in flow of the insulating material which further insures a more uniform density in the loaded sheath than if there were just a sudden shut off. When the roller engages the highest portion of the cam surface 126 the cut-off actuating lever 90 will be rotated clockwise to its original position to shut off completely the flow of insulating material to the sheath.

When the carriage 38 has been moved upwardly an amount sufficient to cause the flow of insulating material to be cut off in the above described manner, the latch 130 will move into engagement with the top surface 131 of the guide rail 34. At the same time, the lower stop 123 engages the control arm 106 and moves it upwardly so that

the lever 99 is moved in a clockwise direction with a snap action. This causes the pawl 169 to be moved out of engagement with the ratchet 166 so as to stop the oscillatory movement of the carriage and also causes the opposite end of the lever 99 to move in position to latch the lever 90 in its position corresponding to the clock position of the gate 89. It will be understood, of course, that the engagement of the roller 127 with the cam surface 126 shuts off the flow of insulating material prior to the movement of the lever 99 and the movement of the lever merely serves to latch the operating lever in its off position.

While the aforescribed filling of a single sheath is proceeding, the entire superstructure including all five of the loading mechanisms shown in Fig. 3 is rotating slowly. In the loading of small sheathed units such as shown in Fig. 19 the flow of insulating material is regulated so that the loading is completed in about three-quarters of a revolution. Thus when a particular loading mechanism passes in front of the operator, the sheath is loaded and ready to be removed. This last step is accomplished by snapping open the jaws 68, disconnecting the upper terminal from the terminal supporting rod 53, and lifting the loaded unit off the protuberance 50 provided on the support 46. A new empty sheath is then quickly mounted on the mechanism in the manner described above and the centralizer lowered to restart the cycle. It will be obvious therefore that the operator can sit before the machine and with empty sheaths and assembled coils conveniently available can operate at a high efficiency.

It occasionally happens that the centralizer 59 sticks in a sheath as the result of too rapid filling of the filling material above the centralizer. In accordance with this invention improved means are provided for quickly and easily freeing the sheath thus clogged. The first step is to pull the bell crank lever 186 forward so that the follower 183 is moved off the cam surface 184. The operator then moves the latch members 57 and 66 so that the supporting blocks for the terminal hook and the centralizer tube may be moved out of their respective recesses. At the same time the jaws which hold the sheath are moved to the open position. The entire terminal rod support, centralizer and sheath are then removed from the loading mechanism and inverted to shake the excess powder out of the sheath until the centralizer is again free to move.

From the foregoing, it will be observed that we have provided a new and improved apparatus which comprises a plurality of separate loading mechanisms so arranged and operated that the efficiency of an operator may be substantially increased. It will also be observed that we have provided a new and improved loading apparatus in which a plurality of separate loading mechanisms are fed from a single hopper thereby reducing the servicing required for the apparatus during its operation. Moreover, we have provided a new and improved means by which the entire centralizer tube, terminal rod and sheath may be removed from the machine as a unit so as to free quickly and readily any jammed or stuck centralizer.

It will be additionally observed that we have provided a new and improved multiple loading machine in which a single driving mechanism may be used to cause the separate units to pass progressively before the operator and to cause the

reciprocation of the individual loading heads. It will also be observed that included in our new and improved loading apparatus is new and improved means for selectively stopping the reciprocatory movement of a particular loading mechanism by completely disengaging its oscillating mechanism from its driving means. Finally it will be observed that we have provided new and simplified means for automatically starting the loading operation when the centralizer is in its lowermost position and stopping the loading operation when the centralizer has been raised in accordance with the filling operation.

While we have described a specific embodiment of this invention, it will be understood, of course, that we do not wish to be limited thereto since many modifications may be made, and we, therefore, contemplate by the appended claims to cover any such modifications as fall within the true spirit and scope of our invention.

What we claim as new and desire to secure by Letters Patent of the United States is:

1. A multiple loading apparatus for a sheathed heater of the type having an outer sheath and a helical resistance conductor in said sheath embedded in a granular insulating material comprising a rotatably mounted platform, a plurality of separate loading mechanisms mounted on said platform, each of said loading mechanisms having a centering member adapted to move in said sheath around said conductor and means for moving said centering member with a reciprocatory motion, means for rotating said platform so that said separate loading mechanisms are progressively passed before a given point, driving means, and means for connecting said driving means to said means for rotating said platform and said means for moving said centering member with said reciprocatory movement so that said platform is rotated at a relatively slow speed and said centering members are reciprocated at a relatively high speed during loading operations.

2. Apparatus for loading a sheathed heater of the type having an outer sheath and a helical resistance conductor in said sheath embedded in a granular resistance material comprising a base member, a platform rotatably mounted on said base member, a plurality of separate loading mechanisms mounted on said platform and adapted to be rotated therewith, each of said separate loading mechanisms including a centering member adapted to move in said sheath around said conductor and an oscillating mechanism for reciprocating said centering member in said sheath, a cam member rotatably mounted in said base member, means for connecting said cam member to each of said oscillating mechanisms, and means for rotating said platform at a relatively low speed and said cam member at a relatively high speed.

3. A multiple loading apparatus for loading sheathed wire heating units provided with a sheath, a resistance conductor in said sheath, and granulated insulating material within said sheath embedding said resistance conductor to hold it in spaced relation with said sheath comprising a base; a platform rotatably mounted on said base; a plurality of separate loading mechanisms mounted on said platform so as to be rotated therewith; each of said loading mechanisms comprising a frame, means for supporting said sheaths to be loaded on said frame, a centralizing member adapted to be inserted in said sheath to centralize said resistance conductor relative to

75 said sheath, and oscillating means for producing

a reciprocatory movement of said centralizer up and down as said sheath is filled with insulating material; a cam member; means for connecting said cam member to each of said oscillating means so as to produce the reciprocatory movement thereof; means for driving said cam member at a relatively high rate of speed so that said oscillating means are reciprocated rapidly; means for driving said platform at a relatively low rate of speed so that said separate loading mechanisms are slowly moved past a station at which said loaded sheaths may be removed and the unloaded sheaths mounted in said separate mechanisms; and means for driving said last two mentioned means from a single motive means.

4. Apparatus for loading a sheathed heater of the type having an outer sheath and a helical resistance conductor in said sheath embedded in a granular resistance material comprising a base member, a platform rotatably mounted on said base member, a plurality of individual loading mechanisms mounted on said platform so as to be rotated therewith, each of said loading mechanisms including a centering member adapted to move in said sheath around said conductor and an oscillating mechanism for reciprocating said centering member in said sheath, a cam member rotatably mounted in said base member, means for connecting each of said oscillating mechanisms to said cam member so that said oscillating mechanisms are reciprocated in accordance with the rotation of said cam member, planetary gear means for rotating said table at a relatively slow speed and said cam at a relatively high speed, and means mounted on said base for driving said planetary gear means.

5. A multiple loading apparatus for loading a sheathed heater of the type having an outer sheath and a helical resistance conductor in said sheath embedded in a granular resistance material comprising a base member, a platform rotatably mounted on said base member, a plurality of loading mechanisms mounted on said platform so as to be rotatable therewith, each of said loading mechanisms including a centering member adapted to move in said sheath around said conductor and an oscillating mechanism for reciprocating said centering member in said sheath, a cam member rotatably mounted in said base member, means extending through said platform for connecting each of said loading mechanisms to said cam member so that each of said oscillating mechanisms is reciprocated in accordance with the rotation of said cam member, and means for disconnecting each of said oscillating mechanisms from said cam member so as to stop selectively the reciprocatory movement of a particular oscillating mechanism.

6. A multiple apparatus for loading a sheathed heater of the type having an outer sheath and a helical resistance conductor in said sheath embedded in a granular insulating material comprising a base member, a platform rotatably mounted on said base member, a plurality of loading mechanisms mounted on said platform so as to be rotatable therewith, each of said loading mechanisms including a centering member adapted to move in said sheath around said conductor and an oscillating mechanism for reciprocating said centering member in said sheath, a cam member rotatably mounted in said base member, a plurality of cam followers engaging said cam member, a plurality of connecting rods each having one end connected to one of said oscillating mechanisms and its opposite end con-

nected to one of said cam followers, means for rotating said cam member so that a reciprocatory movement is imparted to each of said oscillating mechanisms through its respective cam follower and connecting rod, and means supported on said platform for vertically moving each of said connecting rods so as to cause the cam follower secured thereto to be moved away from said cam member and thereby selectively stop the reciprocatory movement of the associated oscillating mechanism.

7. Apparatus for loading a sheathed heater of the type having an outer sheath and a helical resistance conductor in said sheath embedded in a granular resistance material comprising a frame, a vertically movable carriage mounted on said frame, means for removably holding said sheath in an upright position in said frame, a rod adapted to support one end of said resistance conductor, and means adapted to hold the opposite end of said resistance conductor so that said conductor is vertically held in said sheath, a centralizing member adapted to be inserted in said sheath to centralize said resistance conductor, a centralizing tube connected to said centralizing member, means for connecting said supporting rod to said frame, means for connecting said centralizing tube to said carriage, each of said last mentioned means including manually releasable latch means whereby said sheath assembly, supporting rod and centralizing tube may be readily removed from said loading apparatus in the event that said centralizer becomes stuck in said sheath during the loading operation.

8. Apparatus for loading sheathed wire heating units having a sheath and a helical resistance element in said sheath embedded in and supported in spaced relation with the sheath by a compacted granular insulating material, the resistance element being connected at its ends to terminals mounted in the ends of said sheath comprising a frame, means for removably supporting said sheath for loading in a stationary upright position on said frame, means adapted to secure one terminal of said resistance element in the lower end of said sheath, a rod adapted to support the other terminal of said resistance element in the upper end of said sheath, a centralizing member adapted to be inserted in said sheath around said resistance conductor and to hold said conductor in fixed spaced relation with respect to said sheath during the loading operation, a centralizing tube surrounding said rod, means for connecting said centralizing tube to said centralizing member, a carriage vertically movable in said frame, means for detachably securing the upper end of said centralizing tube to said carriage, and means for detachably securing the upper end of said terminal supporting rod to the top of said frame, each of said last mentioned means being manually releasable so that said rod, said centralizing tube and said sheath with the resistance conductor therein may be readily removed from said loading apparatus in the event that said centralizer becomes stuck during the loading operation.

9. Apparatus for loading a sheathed heater of the type having an outer sheath and a helical resistance conductor in said sheath embedded in a granular resistance material comprising a frame, means for holding said sheath in an upright position on said frame, means on said frame for feeding said granular insulating material into the upper end of said sheath, means adapted to hold the ends of said conductor in a

fixed position with relation to said sheath, a centering member adapted to slide in said sheath around said conductor and to hold said conductor in a fixed spaced relation with said sheath, a carriage vertically movable in said frame, means for connecting said centering member to said carriage, reciprocating driving means mounted on said frame, means releasably connecting said reciprocating means to said carriage so that said carriage and said centering member connected thereto may be reciprocated up and down during a loading operation, a vertically depending rod secured to said carriage, a control arm for controlling the releasable connection between said carriage and said reciprocating means, and a pair of stops mounted on said rod adapted to engage said control arm to cause it to be moved from one controlling position to another in accordance with the movement of said carriage on said frame, one of said stops being positioned so that when said carriage is in its lowermost position corresponding to the positioning of said centering member adjacent the lower portion of said sheath said control arm is moved to cause said carriage to be connected to said reciprocating means and when said carriage is in its uppermost position corresponding to the positioning of said centering member adjacent the top of said sheath said control arm is moved to a position causing said carriage to be released from said reciprocating means.

10. Apparatus for loading a sheathed wire heating unit having a sheath, a resistance conductor in said sheath, and a mass of compacted granular insulating material embedding said resistance conductor and supporting said conductor in spaced relation with said sheath comprising a supporting frame, means for supporting said sheath with its resistance conductor in an upright position on said frame, a centering member adapted to slide in said sheath around said conductor and to hold said conductor in

fixed spaced relation with said sheath, a carriage vertically movable in said frame, means for connecting said centering member to said carriage, an oscillating mechanism mounted on said frame and adapted to be moved with a reciprocatory movement up and down relative to said frame, means for releasably connecting said carriage to said oscillating mechanism so that said centering member may be moved with a reciprocatory movement, a vertically depending rod mounted on said carriage, a control arm mounted on said frame for controlling the driving connection between said oscillating mechanism and said carriage, said control arm having 15 one position in which said carriage and oscillating mechanism are interconnected so that the two oscillate together and a second position in which said carriage and oscillating mechanism are disconnected so that said oscillating mechanism oscillates independently of said carriage, and a pair of stops vertically spaced on said depending rod adapted to engage said control arm to move it to its different controlling position in accordance with the position of said carriage 20 25 30 35 40 on said frame, one of said stops being positioned so that when said carriage is in its lowermost position corresponding to the positioning of said centralizing member adjacent the bottom of the unit to be loaded said control arm is moved to the position causing a driving connection to be made between said carriage and said oscillating mechanism, and the other of said stops being positioned so that when said carriage is in its uppermost position corresponding to the positioning of said centralizing member in the upper part of said sheath being loaded, said control arm is moved to the position in which the connection between said carriage and said operating mechanism is broken.

FRANK E. FINLAYSON.
EDWIN C. CHAPMAN.

CERTIFICATE OF CORRECTION.

Patent No. 2,316,683.

April 13, 1943.

FRANK E. FINLAYSON, ET AL.

It is hereby certified that error appears in the printed specification of the above numbered patent requiring correction as follows: Page 3, first column, line 53, for "fo" read --of--; page 9, first column, line 7, for "clock" read --closed--; page 10, second column, line 32, claim 7, after the word "loading" strike out the comma; and that the said Letters Patent should be read with this correction therein that the same may conform to the record of the case in the Patent Office.

Signed and sealed this 8th day of June, A. D. 1943.

Henry Van Arsdale,
(Seal) Acting Commissioner of Patents.
